UNITED STATES PATENT OFFICE.

JAMES M. SIBBIT, OF IMPERIAL, CALIFORNIA.

SOAP SHEET AND METHOD OF MANUFACTURING THE SAME.

1,125,408.

Specification of Letters Patent. Patented Jan. 19, 1915.

Application filed December 31, 1913. Serial No. 809,734.

To all whom it may concern:

Be it known that I, JAMES M. SIBBIT, subject of the King of Great Britain, residing at Imperial, in the county of Imperial and State of California, have invented certain new and useful Improvements in Soap Sheets and Methods of Manufacturing the Same, of which the following is a specification.

10 This invention relates to soap sheets and the process by which such sheets are manufactured.

15 The primary object of the invention is to provide a flexible sheet of the above stated character, which may be of relatively small size, but which will at the same time carry a quantity of soap sufficient, under ordinary circumstances, for a single washing of the face and hands.

20 A further object of the invention is to provide soap sheets which may be bound into flexible tablet form for commercial purposes, or which may be put up in any other suitable manner for convenient use.

25 A further object of the invention is to provide a soap sheet which will be flexible and so constructed as to prevent the soap from cracking or crumbling away from the sheet, when flexed. And the invention also 30 has as a further object to provide means whereby the sheet may be readily manufactured to serve as a convenient substitute for soap as now put on the market, such soap as a rule either being formed in solid cakes 35 or put out in liquid form, and in either of which form its transportation by the user is very inconvenient.

40 In the accompanying drawings: Figure 1 is a perspective view showing my improved soap sheets bound in tablet form, the corner of one of said sheets being illustrated as raised from the rest. Fig. 2 is a detail perspective view of one of the sheets showing the apertures formed therein. Fig. 3 is a 45 longitudinal sectional view taken on the lines 3-3 of Fig. 1. Fig. 4 is a fragmentary transverse sectional view taken through one of the sheets, such view being greatly enlarged and showing the disposition of the 50 soap upon the sheet.

Corresponding and like parts are referred to in the following description and indicated in all the views of the accompanying drawings by the same reference characters.

55 The inconvenience of carrying an ordinary cake of soap, especially to the traveling

public, is well known, since it is necessary to provide a container therefor, as otherwise the soap after each using must either be allowed to first dry before being placed within a satchel, or, if this is impossible, the result is the inevitable soiling of everything with which the cake of soap comes in contact. My improved soap sheet overcomes these difficulties, as it may be easily carried about with the person, the sheet being dry and ordinarily protected by a cover.

In carrying my invention into effect, sheets of suitable paper, cloth, or fabric, indicated in the drawings at 10, are coated with layers 50 of soap 11. This is done by immersing the fabric, which is preferably porous, in a soap solution or soap emulsion. I have found that the fabric, as usually employed, will not absorb a sufficient quantity of the soap 55 for ordinary purposes, or if a plurality of layers of soap are deposited upon the fabric, each layer being allowed to dry before the next succeeding layer is applied, the sheet will readily crack and the layers of soap, 60 so deposited thereon, will crumble off and be wasted. In order that a relatively small sheet may carry a maximum amount of soap, and to avoid the necessity of forming the soap in successive layers upon the sheet, 65 I accordingly form in the paper or fabric 10, before being immersed in the soap emulsion, a plurality of relatively small apertures, indicated at 12. Any desired number 70 of these apertures may be formed in the 75 fabric, as found expedient. The fabric, thus prepared, is immersed in the soap solution and allowed to become thoroughly saturated therewith, the soap forming a thin layer or film on each side of the sheet and forming 80 a solid deposit within the apertures of the fabric. The sheets are then allowed to dry or may be dried by artificial means. In this way, I gain not only the advantage of having each sheet carry a relatively large 85 amount of soap, but the further advantage, in the manufacture of the article, of eliminating the necessity of several times immersing the fabric in the soap solution, in order 90 to secure individual layers or deposits of soap thereon. In thus forming the fabric 95 with the apertures before immersion in the soap solution, each finished soap sheet of convenient size, will carry sufficient soap deposit to suffice for a single washing of the 100 face and hands, thereby making it unnecessary to use more than one soap sheet for 105

each such operation and resulting in a consequent saving of material.

The size of the apertures 12 formed in the fabric 10, may, of course, be varied to a certain degree, but they should only be of such diameter that the soap solution will readily solidify therein. As will be readily apparent, these solid webs 13 of soap extend through the apertures of the sheet 10 and connect and support the layers of soap 11 deposited on each side thereof, thus preventing the layers from cracking and breaking away from the fabric, while, at the same time, the flexibility of the finished soap sheet is not affected. This is an important feature of my invention, in that it provides a flexible soap sheet which may be rubbed between the hands, when washing, without immediately cracking and causing the soap to fall from the sheet.

In Fig. 1 of the drawings, I have illustrated my improved soap sheets as bound in convenient tablet form, indicated at 14, the extremities of the sheets being secured in any suitable manner, as by staples 15, and protected by a covering 16. The sheets may be perforated, if desired, as shown at 17, thus facilitating their removal from the tablet.

While I have shown the sheets as a matter of convenience as bound in tablet form, still, it is to be understood that the fabric may be cut in strips and rolled, or the fabric may be cut into sheets and put up in any other convenient form. It is also to be noted that the soap solution used in producing my improved soap sheets may vary in ingredients according to selection, as for instance, the

sheets may be charged with toilet soap or any other kind of soap desired.

Having thus described the invention, what is claimed as new is:

1. The herein described method of manufacturing soap sheets, which consists in saturating perforated sheets of paper with a soap solution to form a layer of soap on each side of each sheet connected by solid deposits of soap extending through the perforations formed in the sheets, and subsequently drying said sheets.

2. As a new article of manufacture, a sheet of paper having a perforation formed therein and having a solid deposit of soap extending through said perforation.

3. As a new article of manufacture, sheets of perforated paper, each sheet having a layer of soap formed on each side thereof, such layers being connected by solid deposits of soap extending through the apertures formed in the sheet.

4. As a new article of manufacture, a flexible sheet of paper having a plurality of apertures formed therein and having a layer of soap formed on each side of the sheet, the soap being formed in solid webs within said apertures, said webs connecting the layers of soap on the sides of the sheet and supporting said layers.

In testimony whereof I affix my signature in presence of two witnesses.

JAMES M. SIBBIT. [L. s.]
